INTERMITTENT FLOW DEVICE

Edward E. Peake, La Salina, Venezuela, assignor
to Standard Oil Development Company, a cor-
poration of Delaware

Application August 31, 1939, Serial No. 292,765

4 Claims. (Cl. 103—232)

The present invention is directed to a bottom hole intermittent flow device for gas lift wells. More specifically, it is directed to an attachment for a string of tubing containing a valve arrangement which automatically permits creation of a head of oil under the formation pressure above the valve and the injection, into said head of oil, of a stream of high pressure gas to lift the oil to the surface.

Innumerable types of gas lift arrangements have been devised for use in oil wells. The majority of these are complicated valve systems which are attached to the flow line between the formation and the surface. Others take the form of borehole pumps which are ordinarily quite complicated in structure and operation.

The principal object of the present invention is the provision of a device of the character described which is simple in character and construction and compact in size.

An additional object of the present invention is the provision of a device of the character described in which the gas inlet passages are not controlled by small valves which become sanded up and corroded, resulting in considerable waste of gas, but in which the ports are simple passages the ends of which are sealed by a valve of the gate type when it is desired to shut off the flow of gas.

Further objects and advantages of the present invention will appear from the accompanying drawing in which the single figure is a vertical section through the tubing attachment of the present invention.

Referring to the drawing in detail, numeral 1 designates a length of tubing having each of its ends provided with threads 2 for attachment to a conventional string of oil well tubing. Adjacent its upper end the section of tubing 1 is provided with an interior collar 3, the lower face 4 of which is frusto-conical in shape to form a seat for a valve 5 which is solid block of metal having, in general, the shape of an inverted cup and saucer and having its upper face shaped to seat on face 4 of collar 3. The valve 5 is provided with a hollow stem 7 which passes through a disc 8 screw threaded into the interior of section 1. The cup shaped portion 9 of the valve 5 is solid and seats on the upper face of disc 8 which is provided with a series of spaced ports 10.

The lower end of stem 7 is provided with a collar 11 between which and the lower face of the disc 8 is arranged a spring 12 which normally tends to hold the valve 5 seated on disc 8.

The passage in the hollow stem 7 continues

5 through the body of the valve 5 and terminates in shoulder 13 on which seats a ball 14 which is restrained from undue movement by a screen 15 screwed into the face of valve 5. The saucer portion of valve 5 is provided also with a series of spaced ports 16. Between the valve 5, when it is seated on disc 8, and the collar 4, the section of tubing 1 is provided with circumferentially spaced radial passages 17.

In practice, this section of tubing 1 is included in the ordinary string of tubing at a point sufficiently near the bottom so that under ordinary formation pressure a considerable head of oil

15 will be built up above section 1. The section is fitted with a conventional type of packer at a point below ports 17 and when the tubing is in place the packer is set against the casing so as to seal off the casing above section 1 from the formation.

20 When the assembly is set in place the pressure of the formation pushes the valve 5 upwardly against the seat 4 thereby closing ports 17 and permitting oil to flow from the formation through ports 10 and 16 up into the tubing. High pressure gas is introduced into the casing. As the head of oil above the valve increases, the spring 12 tends to force the valve back onto its lower seat. As the valve progresses downwardly, it uncovers ports 17 admitting high pressure gas.

25 30 Immediately upon admission of the high pressure gas the valve is snapped onto its lower seat. The high pressure gas then forces the oil in the tubing upwardly until the pressure head on the valve 5 is released whereupon the formation pressure again forces the valve upwardly closing port 17 and beginning the cycle of operation over.

35 It will be apparent that by suitably adjusting the strength of spring 12 to the formation pressure, the amount of head of oil which can be built up for each cycle can be regulated.

40 The ball valve 14 is provided to relieve some of the formation pressure so that valve 5 will seat on its lower seat. If spring 12 is sufficiently strong the ball valve can be omitted.

45 The nature and objects of the present invention having been thus described and illustrated, what is claimed as new and useful and is desired to be secured by Letters Patent is:

50 1. An intermittent flow device for an oil well tubing string comprising a section of tubing adapted to be connected in the string of tubing having a valve seat arranged in its interior and containing circumferential ports in its walls, a valve slidable in said section adapted to control the flow of fluid through said section of tubing

to assume an open and a closed position and to be forced into open position by formation pressure, said valve being arranged to close said ports when in its open position and to fit against said seat when in its closed position, and means for normally urging said valve to its closed position.

2. A device in accordance with claim 1 in which said valve is provided with a longitudinal passage having a closure which opens under less formation pressure than said valve.

3. An intermittent flow device for an oil well tubing string comprising a section of tubing adapted to be connected in the string of tubing, the interior of said section being of smaller diameter in a median portion than at its ends, a perforated plate laterally arranged in said small diameter portion, said section having longitudi-

nal walls extending a short distance on one side of said plate, a valve in said section arranged to seat on said perforated plate and having a smaller diameter portion slidable in the reduced diameter portion of said section, a larger diameter slidable in the enlarged portion of said section and an intermediate portion, passages connecting said intermediate portion to the enlarged diameter end of said valve, circumferential ports arranged in said section to be exposed when said valve is seated and to be covered by said valve when it is moved away from its seat, and means for normally urging said valve to its seat.

4. A device in accordance with claim 3 in which the valve is provided with a longitudinal passage controlled by a ball valve.

EDWARD E. PEAKE.
